(57) **CLAIM**

I claim the ornamental design for a glove upper, as shown and described.

DESCRIPTION

FIG. 1 is a perspective view of a glove upper showing my new design;

FIG. 2 is a front perspective view thereof;

FIG. 3 is a rear perspective view thereof;

FIG. 4 is a right side elevation view thereof;

FIG. 5 is a left side elevation view thereof;

FIG. 6 is a top perspective view thereof; and,

FIG. 7 is a bottom perspective view thereof.

The broken lines in the figures depict environmental structure and form no part of the claimed design.

1 Claim, 6 Drawing Sheets
